UNITED STATES PATENT OFFICE.

CLARENCE M. HOLLEY AND EARL P. OSWALD, OF DETROIT, MICHIGAN, ASSIGNEES, BY
MESNE ASSIGNMENTS, TO THE HOOVER COMPANY, OF NORTH CANTON, OHIO, A
CORPORATION OF OHIO.

MECHANICAL UNLOADING DEVICE FOR COMPRESSORS.

Application filed December 24, 1919, Serial No. 347,134. Renewed April 6, 1925.

To all whom it may concern:

Be it known that we, CLARENCE M. HOLLEY and EARL P. OSWALD, citizens of the United States, residing at Detroit, county of Wayne, State of Michigan, have invented a certain new and useful Improvement in Mechanical Unloading Devices for Compressors, and declare the following to be a full, clear, and exact description of the same, such as will enable others skilled in the art to which it pertains to make and use the same, reference being had to the accompanying drawings, which form a part of this specification.

This invention relates to automatic load control devices for compressors, the object being to provide a mechanical device for automatically unloading a compressor for air or other fluids when idle to relieve the motor of the load during the starting period. Compressors for a refrigerant used in artificial refrigerating systems are usually operated by an electric motor and usually the compressors remain under the load of the high pressure side of the circulating system when not in operation and thus a motor is required of greater capacity and current consumption to start under the load than is required when operating at full speed. The object of this invention is to provide mechanism to automatically release the compressors of the load in order that a motor of comparatively small starting torque and small current consumption may be utilized, as a motor when under full speed can assume a load which is in excess of its capacity during the starting interval. The principal feature of this invention is involved in the use of centrifugally operated mechanical appliance adapted to open the valves of the compressor when operated below a predetermined speed and thus permit the motor to start and operate up to the time of attaining the predetermined speed without assumption of full load of the compressor. A further object of this invention is to provide a motor and compressor outfit for an artificial refrigerating system in which the motor and compressor unit is enclosed within a part of the circulating system preferably on the low pressure side thereof and to provide in conjunction therewith mechanism actuated by centrifugal force to hold the intake valves open and

permit the pistons of the compressor to 55 operate without transference of the fluid from the low to the high pressure sides of the systems until a certain predetermined speed is attained whereupon the intake valves are permitted to close and operate in 60 the normal manner. These and other objects and the several novel features of the invention are hereinafter more fully described and claimed, and the preferred form 65 of construction of the invention is shown in the accompanying drawings in which—

Fig. 1 is an elevation partly in section showing the compressor and motor unit in a portion of the circulating system of an artificial refrigerating apparatus.

Fig. 2 is a section taken on line 2—2 of Fig. 1 showing the compressor unit in plan view.

Fig. 3 is an enlarged section through the head of the motor showing the inlet valves 75 and portion of the cylinders.

Fig. 4 is an elevation partly in section showing the control apparatus in position assumed to open the inlet valve of the compressor when the motor is idle.

Fig. 5 is a similar view showing the control apparatus in the position assumed when under operation releasing the valve to its normal operation.

The electric motor 1 and the compressor or pump unit 2 are enclosed within a casing 3 into which the low pressure line 4 of an artificial refrigerating system opens and from which the high pressure line 5 leads, the high pressure line being directly connected by a pipe 6 with said discharge line. This construction and relationship of the casing or chamber 3 with an artificial refrigerating system and the function thereof is set forth and described in our pending application Serial No. 329,469 filed October 7, 1919. The motor as is set forth in the said former application is provided with a shaft 7 having a worm 8 thereon meshing with a worm wheel 9 on the crank shaft 10 of the motor and, as will be understood from Fig. 3, preferably there are two cylinders 11 and 12 having reciprocable pistons therein connected with the crank shaft in the usual manner of compressors. Each compressor is provided with an intake valve 13 and an exhaust valve 14, both of which are to be understood as being spring-seated

valves of the usual type. The inlet valves both open to a chamber 15 which is open, by means of the aperture 16, to the interior of the casing 3 from which the compressors 5 receive the fluid to be compressed. The check valves 14 each open to a chamber 17 individual thereto which are to be understood as connected together and discharging into the conduit 6 leading to the discharge line.

In operation of these compressors the refrigerant fluid is drawn through the orifice 16 and past the valves 13 into the cylinders of the compressor which alternately draw 15 fluid thereinto and discharge therefrom under pressure to the high pressure line. Heretofore, to operate these pistons in the compressors, the pistons on the initial up-stroke must compress the fluid in the cylinders to a degree slightly in excess of the pressure of the high pressure line in order 20 to discharge the same thereinto and with an electric motor operating the pistons this initial load requires a motor of greater capacity than is required after the motor has 25 attained full speed. Thus, generally, a motor of excessive current consumption and of comparatively high first cost has necessarily been heretofore utilized. This invention 30 seeks to provide an automatic mechanical device for opening the intake valves 13 when the compressor is at rest or operating below a certain predetermined rate of speed. This is accomplished by means of a 35 lever 18 pivoted at 19 adjacent each intake valve and provided with a rounded end 20 adapted to engage the upper end of the valve stem; there being a lever for each intake valve of the several compressors that 40 may be utilized. This lever at a point remote from the pivot point has a plunger 21 connected thereto by a pin 90 extending through a slot 91 in the lever. The plunger extends through a housing 22 in which it is 45 movable longitudinally. This housing is mounted in a bushing 23 supported in a boss on the casting 24 forming part of the head of the compressor in the construction here shown. The housing 22 has provided on the 50 lower end thereof a gear 25 with which meshes a gear 46 secured to the motor shaft 7. Rotation of the motor shaft rotates the gear 25 and housing 22 about the plunger 21. The gear 25 has a pair of lugs 26 and 55 27 depending from the lower side thereof to which are pivoted the plunger operating dogs 28 each similar in character and each having an end 29 adapted to engage the lower end of the plunger 21 as will be understood from Fig. 4. These dogs 28 are 60 weighted at the lower end and are connected together by a spring 30 tending to draw them to the position shown in Fig. 4 raising the plunger 21 through its housing 65 and depressing the stem 31 of each intake

valve 13 and opening the valves. It is to be noted that this spring 30 acts when the shaft 7 is idle or operating at a speed insufficient to cause the weighted dogs to be thrown outward by centrifugal force exceeding the tension of the spring 30. Thus, when the motor is idle or while it is starting and up to the point where the centrifugal action is not sufficient to cause the dogs to be thrown outward at the weighted ends 75 as stated, the inlet valves are held open and the pistons may operate in the cylinders, the only load placed upon the motor being the friction caused by the movement of the piston in the cylinders. With the inlet valves held open, the fluid is drawn into the cylinders and moved outward through the intake valves only and thus an electric motor of small capacity and small starting torque 80 may be utilized with the control mechanism 85 described.

Upon the motor shaft 7 attaining sufficient speed to cause the dogs to be thrown outward at the weighted ends, as shown in Fig. 5, the valve spring operating on the stem 31 closes the valve as the plunger is permitted to move downward through its housing due to the ends 29 being withdrawn from the lower end thereof. These dogs 28 will assume this position during the time 90 of operation of the motor at full speed and the pump will perform its normal function of taking in the fluid through the intake ports and discharging the same through the 95 exhaust ports, the valves normally operating in their designed manner. Immediately upon cessation of operation of the motor and its speed being reduced below that sufficient to cause actuation of the weighted dogs as described, the spring 30 draws the 100 weighted ends of the dogs together and raising the ends 29 against the plunger 21 and which, by reason of the leverage of the lever 18, opens the valves holding the same 105 open until the motor is again operated. 110

The mechanism is simple in the extreme and while we have shown two compressors, one or any number of compressors may be employed as may be desired. Preferably, each intake valve should be provided with 115 centrifugal valve operating apparatus tending to open the same during the idle period of the motor as heretofore stated.

We are aware of other mechanism in which the intake valves are opened upon current being applied to the motor to start the same. The herein described mechanism differs from such former type of mechanism as these valves 13 are opened immediately upon cessation of operation of the motor shaft. This is preferable for the reason that valves remaining closed for a long period are apt to stick due to the fact that the intake valves are open to the low pressure side of the refrigerating system and 120 125 130

therefore subject to comparatively low temperatures. With this mechanically operated device the valves are opened in reality before the pistons have ceased operation and thus are opened prior to there being possibility of their freezing to the seat.

Having thus fully described our invention, what we claim and desire to secure by Letters Patent of the United States is—

- 10 1. In a fluid pressure system, the combination with a compressor having a high and a low pressure line, of a casing or chamber forming part of the low pressure line and enclosing the compressor, an inlet valve of the compressor opening to the chamber, a discharge valve for the compressor opening directly to the high pressure line, a motor in the chamber, and a centrifugally operated means within the chamber driven by the motor and acting to hold the inlet valve open to the chamber until the motor has attained a predetermined speed of operation.
- 20 2. In a fluid pressure system, the combination with a compressor having a high and a low pressure line, of a casing or chamber forming part of the low pressure line and enclosing the compressor, said compressor comprising a pair of cylinders operating in alternate relation, a motor in the chamber having a shaft occupying a vertical position adapted to operate the compressors, each compressor having a spring closed inlet valve opening to the chamber and a discharge valve opening directly to the high pressure line, a pivoted lever for each inlet valve, one end of each lever engaging the stem of the inlet valve, weighted levers tending when idle to actuate the lever to depress the inlet valve stem and open said valve, a gear for each pair of weighted levers by which the same may be rotated, a spring tending to draw the weighted levers together and hold the inlet valve open, and a gear on the motor shaft meshing with both of said first named gears whereby the weighted levers are rotated through rotation of the lever shaft and the valves released upon attainment of the predetermined motor speed.
- 30 3. In a fluid pressure system, the combination with a compressor having a high and low pressure line, of a casing or chamber forming a part of the lower pressure line and enclosing the compressor, a motor in the chamber for operating the compressor, a spring closed inlet valve for the compressor opening to the chamber, a discharge valve

for the compressor opening directly to the high pressure, a pivoted lever having an end engaging the stem of the inlet valve, a centrifugally operated means for actuating the lever to release the inlet valve to its spring, said centrifugal means being directly connected with the motor shaft whereby the speed of the motor directly controls the release of the inlet valve.

4. A mechanical unloading device for fluid compressors comprising the combination with a compressor having a spring closed inlet valve, an electric motor for operating the compressor, of a lever pivotally mounted upon the compressor head having one end engaging the valve stem, a plunger or rod at the opposite end of the lever, a centrally apertured housing in which the rod is movable longitudinally, a gear on the said housing, a gear on the motor shaft meshing therewith, and means operated through centrifugal force caused by rotation of the gear and housing to release the rod and lever to permit normal operation of the inlet valve, said centrifugally operated device being adapted when idle or operating below a predetermined speed to cause movement of the lever to open the inlet valve against the tension of the valve spring.

5. A mechanical unloading device for fluid compressors comprising the combination with a compressor having a spring closed inlet valve, an electric motor for operating the compressor, a lever pivotally mounted upon the compressor head and having one end engaging the valve stem, a reciprocable rod connected with the opposite end of the lever, a centrally apertured housing in which the rod is movable longitudinally, a gear on the said housing, a gear on the motor shaft meshing therewith, a pair of weighted levers pivotally supported on the housing gear, each having an end extending beneath the end of the rod, a spring tending to draw the weighted levers together forcing the rod longitudinally of the housing against the tension of the valve spring and normally holding the valve open, the tension of the spring predetermined the centrifugal force required to cause the said ends to swing outward permitting the valve to close by action of its spring.

In testimony whereof, we sign this specification.

CLARENCE M. HOLLEY.
EARL P. OSWALD.
